PUMP

Galen Evans, Shelton, Nebr.

Application March 6, 1931. Serial No. 520,540

2 Claims. (Cl. 103—102)

My invention relates to wells and particularly to wells of the type which are sunk and operated in a soil of water-bearing sand and gravel.

One of the objects of the invention is the provision of a well structure which may be easily sunk in the soil stratum for which it is designed.

Another object of the invention is to provide an entire pump assembly which will constitute the well casing after the pump assembly has been put into place.

Another of my objects is the provision of a pump assembly including a strainer at the lower extremity with rotary pump bowls and with a pump column all forming a unitary structure.

One of the more important objects of my invention is the provision of a pump assembly including a strainer having a greater cross sectional area than the pump column.

Still another object of the invention is the provision of a pump assembly having a strainer, the whole structure being so arranged that the strainer may be easily desanded.

Having in view these objects and others which will be pointed out in the following description, I will now refer to the drawings, in which

Figure 1 is a view in elevation of the pump assembly, the soil being sectioned and a portion of the pump column being broken away.

Figure 2 is a view similar to Figure 1 but showing the arrangement of the pump bowls at a greater distance above the upper surface of the strainer.

Figure 3 is a view similar to Figure 1 but showing the pump bowls arranged so that they will be partly within the strainer and partly above.

Figure 4 is another view similar to Figure 1 but showing the arrangement with all of the pump bowls within the strainer.

Figure 5 is a vertical sectional view of the pump. The entire pump assembly includes a strainer element 10, one or more rotary pumps 11 and a pump column 12. A motor 13 of any suitable type drives the shaft 14 which drives the impellers 15, the impellers being secured to the shaft 14 against rotary and sliding movements. The diameters of the pump elements 11 and of the pump column 12 are less than the diameter of the strainer element 10.

The pump 11 is a rotary pump and it may consist of a single pump element or of two or more elements arranged in stages. The pump may be directly above the strainer 10 as shown in Figure 1 or it may be at any suitable distance above the strainer as shown in Figure 2 or it may be partly inside and partly outside the strainer as

shown in Figure 3 or it may be entirely inside the strainer as shown in Figure 4. In every case it is provided with an intake 16 for drawing the water from within the strainer 10.

The pump itself is best shown in Figure 5. This figure shows the pump in five stages but it is obvious that any number of pump elements may be employed depending on the conditions surrounding the particular job. In every case, however, the pump includes an intake 16 together with one or more pump bowls 11 and with a pump column 12. The impellers 15 may all be equal in diameter or they may be made in diameters which successively decrease from the uppermost to the lowermost. The decrease would be very minute but it must be sufficient to permit the passage of each impeller through the throat of the bowl immediately above. Below the lowermost bowl 11 the intake 16 is provided with an annular shoulder for supporting the lower bearing support 17. This support is in the form of a spider having an outer annular ring which seats on the shoulder of the intake 16. The bearing itself is shown at 18. The shaft 14 passes through this bearing 18 and it is provided with a head 19 which seats against the lower edge of the bearing support 17. Since the impellers 15 are secured to the shaft 14, the position of the bearing support 17 on the shoulder will insure that they assume their proper positions in the assembly of the pump, it being only necessary to make sure that the impellers are properly positioned on the shaft 14, where they are locked in place by means of pins 20 or any other suitable fastening devices such as keys. The shaft 14 is also provided with an upper bearing 21 in a spider 22 having a frusto-conical lower edge for seating on the shoulder 23 of the pump column 12.

The well and pump assembly is designed particularly for use in soils having very little clay and which consist almost entirely of water-bearing sand and gravel of all degrees of fineness and coarseness. Such soils are very common near numerous streams such as the Platte and they are very difficult to handle both in the sinking of a well and in the continued operation of the well. The ordinary boring or drilling methods do not succeed because of the looseness of the sand and gravel and it is therefore necessary to sink the well by removing the sand or gravel from beneath and around the well so as to permit the sinking of the casing by gravity. After the well has been sunk it is very apt to clog up slowly by the fine sand which lodges in the apertures of the strainer of the well. It is well known that a

filter of coarse gravel about the strainer will usually prevent the fine sand from stopping the flow in the ordinary domestic wells where the water is used to supply the kitchen and live stock. In 5 high capacity wells, however, the demands on the water supply are so heavy that the fine sand is apt to be drawn through a portion of the gravel filter and to thus materially reduce the capacity of the well by filling the interstices in the gravel 10 mass. The pump assembly as above described has been designed particularly to solve these difficulties.

The well is assembled in the manner indicated in the drawings and it is sunk by removing the 15 soil from underneath and surrounding the strainer, the pump column, bowls and strainer being first secured together. Any suitable method for sinking it may be employed such as that disclosed in my prior Patent Number 1,733,953, issued October 29, 1929. As the soil is removed from underneath the strainer, the weight of the well assembly carries it downward and the operation is then stopped when the strainer 10 has reached the desired depth. Ordinarily a retaining wall must 20 first be constructed to prevent the loose soil from falling into the cavity but this retaining wall may be of a temporary nature. As soon as the well has been sunk to the desired depth, the soil is allowed to fill in about the parts of the well as 25 shown in Figure 1. The pump bowls 11 and the pump column 12 then become the entire well casing 30 above the strainer 10.

When the strainer 10 or the gravel filter about the strainer 10 becomes clogged by fine sand filling the interstices between the gravel particles as 35 shown by the decreased capacity of the pump, the fine sand may be easily dislodged by means of my well and pump assembly. The pump column 12 maintains a considerable head of water while the 40 pump is in operation. If suddenly released by the stopping of the motor, the water will suddenly drop back into the strainer with considerable force and it will pass out to loosen any fine sand particles which may have become lodged in 45 the strainer or in the gravel filter. If this process is repeated several times, the fine sand particles will either be drawn into the strainer 10 where they will pass out through the pump or they will be forced back into the soil a sufficient 50 distance so that they will not interfere with the operation of the well. The process may also be carried out by employing a reservoir similar to that shown and described in my prior application, Serial Number 449,914, filed May 5, 1930. By 55 repeatedly starting up and stopping the pump suddenly to fill up and to drain the reservoir, the strainer and the surrounding gravel may be thoroughly washed to remove all of the fine sand which normally hinders the free flow of water 60 into the well. It should be noted that the clogging usually takes place in the direction of the normal flow of water from the soil into the well. The back wash when the water is flowing from the pump column or reservoir into and through 65 the well is more apt to dislodge the particles of fine sand than is possible when the water is flowing into the well from the soil.

It has heretofore been the practice of providing a well casing surrounding the bowls 11 and the 70 column 12. In such installations the entire pump assembly must be removed whenever repairs become necessary. Such an assembly is much more costly of installation than the one which I have described. I have found, however, that the only 75 parts of the pump installation which ordinarily

require repair are the impellers. The pump bowls as a rule are of solid construction and they are not liable to develop any trouble during the operation of the pump aside from the effect of the slight wear at the shoulders adjacent the impellers. When the impellers require repair in my pump it is only necessary to first remove the motor 13 and to draw out the shaft 14 with the two bearing supports 17 and 22 and with all of the impellers 15. Since the throats in the pump bowls are either all of the same size or of slightly increasing diameters from bottom to top, it is possible for all of the impellers to pass through all of the throats above. The repairs can then be easily made since it is not necessary to separate the bowls from each other. After the repairs are made the impeller assembly with the shaft 14 and with the two bearing supports is again placed into the well until the two bearing supports rest on the shoulders provided for them. The removability of the shaft with the impeller assembly also makes it possible to gain access to the well for cleaning out the well.

All wells regardless of their construction must get their water supply from the original soil formation. Unless this soil formation is improved, the well is short-lived as it very quickly becomes clogged up by the fine sand so that little water can enter the strainer. A prior method of improving this soil formation consists in surrounding the strainer with a thick layer of coarse gravel. By the prior methods this is a very difficult process owing to the fact that the sand and gravel naturally and quickly flow into any cavities in a soil of that kind. If the strainer is sunk into the sand and gravel soil it is a very difficult matter to excavate a cavity at its sides and surrounding the strainer and of sufficient thickness to fill in with an effective gravel deposit. My method, however, contemplates the desanding of 105 the layer of sand and gravel surrounding the strainer, this desanding method being useful in sinking the well casing with the strainer and also at any time during the life of the well when the surrounding soil layer becomes too heavily impregnated with fine sand. The method is an 110 exceedingly simple one since it involves only the action of water which is applied by means of the equipment forming part of the well and pump.

Having thus described my invention in such full, clear, and exact terms that its construction and operation will be readily understood by others skilled in the art to which it pertains, what I claim as new and desire to secure by Letters Patent of the United States is:

1. A combined well and pump consisting of a pump column and a plurality of pump bowls and a strainer secured together in vertical relation, each of said pump bowls being in the form of a spheroidal shell having an inner annular shoulder 135 and having an impeller positioned immediately above the level of said shoulder, the internal shoulders of said bowls having the same diameters and the diameters of said impellers being slightly less than the diameters of the bowl shoulders, and a vertical shaft secured to all of said impellers and terminating above the upper extremity of said pump column, said pump column and said pump bowls and said strainer constituting the sole casing for said well.

2. A combined well and pump including a pump column and a plurality of pump bowls and a strainer secured together in vertical relation and imbedded in the soil and having said strainer surrounded by relatively coarse gravel, each of 140

said pump bowls being in the form of a spheroidal shell having an inner annular shoulder and having an impeller positioned immediately above the level of said shoulder, the internal shoulders 5 of said bowls having the same diameters and the diameter of each impeller being slightly less than the diameter of any bowl shoulders, and a ver-

tical shaft secured to all of said impellers and terminating above the upper extremity of said pump column whereby said shaft and all of said impellers may be withdrawn as a unit from said well.
